(57) **CLAIM**

The ornamental design for a handheld electronic device, as shown and described.

DESCRIPTION

FIG. 1 is a perspective view of a handheld electronic device showing my new design with the strip stand curved;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view thereof, showing the handheld electronic device in an alternate position of use.

The broken line portions of the handheld electronic device in all views represent unclaimed portions of the claimed design and form no part thereof.
